Primary Examiner — Selina Sikder(74) *Attorney, Agent, or Firm* — Wenderoth, Lind & Ponack, L.L.P.(57) **CLAIM**

The ornamental design for a switch, as shown and described.

DESCRIPTION

FIG. 1 is a top perspective view of a switch showing an upper surface with front and left side surfaces;
 FIG. 2 is a bottom perspective view thereof showing a bottom surface with rear and right side surfaces;
 FIG. 3 is a front view thereof, a rear view being identical to FIG. 3;
 FIG. 4 is a top plan view thereof;
 FIG. 5 is a bottom plan view thereof; and,
 FIG. 6 is a left side view thereof, a right side view being identical to FIG. 6.
 The broken lines shown herein are for illustrative purpose only and form no part of the claimed design.

1 Claim, 3 Drawing Sheets(56)
